PAPER FEEDING DEVICE

George T. Fyfe, Toronto, Ontario, and John G. Catterall, Lansing, Ontario, Canada, assignors to International Business Machines Corporation, New York, N. Y., a corporation of New York

Application September 5, 1936, Serial No. 99,540

12 Claims. (Cl. 197—133)

This invention relates generally to devices for controlling feeding of a record sheet in printing machines and more specifically to a check feeding control mechanism in a record controlled 5 tabulator.

An object of the invention is to provide improved means for rapidly and accurately feeding checks through an accounting machine.

Another object is to provide means under control of marginal perforations in the checks for locating them in proper printing position. A frictional gripper is operated to hold the check strip in an accurate position at a point determined by perforation sensing devices.

Another object of the invention is to provide a check feeding device which is operative as an incident to name printing and total printing.

A feature of the invention is the provision of means for selecting ordinary sheet spacing or 20 check feeding control.

An object of the invention is to make it easy to thread a check strip in a feeding mechanism and for this purpose there is provided a hinged cover on a paper aligning unit and a clutch release device for freeing a platen for manipulative control.

Another feature is the selection of one of a plurality of sensed marginal perforations to control feeding.

The foregoing and other objects of the invention will be evident as this specification continues with reference to the drawings forming a part thereof.

In the drawings:

Fig. 1 is a plan view of the perforation sensing and paper gripping control unit.

Fig. 2 is a right sectional elevation view of the gripper unit with the section taken along the line 2—2 in Fig. 1.

Fig. 3 is a sectional elevation view of the gripper unit looking from the rear at a section along line 3—3 in Fig. 1.

Fig. 4 is a right elevation view of the paper feeding devices.

Fig. 5 is a front elevation view of the paper feeding devices.

Fig. 6 is a sectional view of the paper feeding clutch devices looking down at a section taken along the line 6—6 in Fig. 4.

Fig. 7 is a detail view of a section of the check strip showing two printed checks.

Fig. 8 is an elevation view of the printing devices.

Fig. 9 is a wiring diagram.

The invention is illustrated as an improvement

in machines of the type disclosed in the application of A. W. Mills, Serial No. 634,454, filed September 23, 1932, which matured as Patent 2,079,418 and U. S. Patent 2,016,682. In these machines, perforated record cards contain numerical and alphabetic data which is sensed to control accumulation and printing. The records are arranged in groups according to perforated group numbers so that a series of items may be added to form a total amount related to the group. Automatic group control devices detect a change in group numbers and initiate total printing. A group number or a name may be printed as an incident to the sensing of the first card of a group and then printing may be suspended until the total amount of the group is printed. Such first card printing control is fully explained in the application of J. R. Peirce, Serial No. 620,653, filed July 2, 1932. In the present case a name is printed on a check and then a related total amount is printed on the same check before the check strip is fed to position another check in printing position.

In Fig. 7 there is shown a sample section of a check strip 50 which is divided into separate checks of a regular form and length. The sides of the strip are perforated with marginal perforations 51 which not only serve to control the positioning of the checks, but also aid in subsequent feeding operations when the strip is removed from the tabulator. The distance that the strip is fed between printing operations is illustrated at the left of the strip.

The strip 50 is held against a platen 52 (Fig. 8) and there receives the printing impressions. The printing mechanism may be explained in a general way with reference to Fig. 8. A printer control magnet PM is energized at a differential instant according to the time of sensing a perforation in the record card or the time that an accumulator controlled total contact is closed. Moving in synchronism with the other tabulating mechanism is a type bar 53 formed with notches 54 that are moved in succession past a stop pawl 55. When magnet PM is energized it attracts an armature lever 56 to which is attached a call wire 57 connected at the opposite end to a latch 58 for releasing pawl 55. Thus the type bar 53 is stopped differentially by the pawl engaging in one of the notches 54; the bar stopping between a hammer 59 and platen 52 to place at the printing line, a type 60 corresponding to the perforation or total sensed.

As the check strip 50 is threaded up to the platen 52, it is passed through the perforation

sensing and paper gripping control unit shown in Figs. 1, 2 and 3. This unit is mounted in a box made up with a pair of rigid side bars 61 and 62 (Fig. 3) to which are fastened the top plate 63, the side plates 64, 65 and the base plate 66, (Fig. 2). The plates 64, 65 are notched to hook on a tabulator shaft 67 and the unit is fastened so that the front end of the top plate 63 overlaps the paper guide 68.

10 The check strip 50 passes between side guides 69 and 70 fastened to the top of bars 61, 62. Guide 69 is fixed but guide 70 is adjustable because transverse slots 73 therein may be shifted under the fastening screws 71. The strip slides 15 freely between plate 63 and a bakelite cover 72 which is hinged at 74 on the side plate 65 and provided with a pair of fastening screws 75 for holding the cover closed.

10 The paper strip confining members of the gripper unit dispense with the need for lateral guides for the strip and the hinged cover makes it easy 20 to insert a new length of strip. Thus the feed correcting unit acts as a paper guide to replace the regular angular members used in fanfold 25 work.

Cooperating with the left margin of the check strip 50 (Fig. 3) is a leaf spring contact 76 fastened to an insulation block 77 secured to bar 62. Opposite the pointed ends of contact 76 is a 30 metallic insert 78 in cover 72. When a marginal perforation 51 passes above contact 76, it reaches through and touches the insert to establish part of an electric circuit.

Even though the insert 78 is mounted on the 35 movable cover 72, provision is made to carry current thereto from a fixed binding post 82. A screw 79 threaded in the insert 78 clamps a wire 80 to the top of cover 72. At its other end, wire 80 is held over a spring contact 81 fastened to 40 the top of cover 72 by screws 83. The end of contact 81 carries a point 84 which contacts the top of the head of the screw 85 forming part of binding post 82. The screw passes through an insulation washer 86, an insulation bushing 87 and 45 a fibre block 88 which serve to keep the wiring insulated from the frame. When the cover 72 is lowered contact is established between point 84 and screw head 85 to convey current from binding post 82 to the perforation sensing contact 76. 50 However, as soon as the cover is swung about hinge 74 the contact points are separated to break the connections.

An additional cover 69 protects the wire 80 from being grounded. The perforation sensing 55 contact 76 passes through all of the marginal perforations on one side of the check strip as it is being fed. The gripper magnet GM connected therewith is not operated for each perforation because at another point in the circuit, contacts are 60 opened for most of the cycle and closed only at a critical point when the strip approaches the end of the feeding movement, as explained more fully hereinafter with reference to the wiring diagram.

When such a critical point in the feeding cycle 65 is reached, the contact 76 protrudes through a selected marginal perforation 51 and contacts against the underside of insert 78 thereby energizing the gripper magnet GM. This magnet is supported on a U-shaped bracket 89 fixed to the 70 underside of the top plate 63. Overlying the magnet GM is an armature portion 90 of a gripper lever 91 pivoted on a shaft 92 secured to the underside of the bars 61, 62. A pair of collars 93 hold the lever 91 in position on shaft 92 but free 75 thereon for rocking movement. The front end

of the lever carries a pair of brackets 94 to which is secured a rectangular friction plate 95. The top of the plate is notched to hold a rubber friction block 96 underlying the center of the check strip 50 (Fig. 1). The strip passes between the 5 underside of cover 72 and the top of friction block 96 as shown in Fig. 2. There it is seen that when magnet GM is energized, gripping lever 91 is rocked in a clockwise direction to press the rubber block 96 against the underside of the check 10 strip, forcing it against the cover plate 72 and holding the strip in a position determined by the position of the marginal perforation 51 with relation to the sensing contact 76. The gripper prevents further movement of the strip when a 15 perforation is sensed near the end of the feeding operation.

When the cover 72 is closed it serves to operate a pair of contacts 97, 97a wired in the gripping control circuit to prevent strip sensing operation 20 as long as the cover is raised. The cover carries a plunger 98 (Fig. 2) provided with a rubber tip 99 pressing against the top blade of the set of contacts 97 to close the contacts when the cover 25 72 is down. The contact blades are tensioned to 98. automatically open when the cover raises plunger

The feeding devices about to be described are 30 designed to feed the check strip to a distance slightly greater than the height of a check form 35 and slightly greater than the distance between a plurality of spaced marginal perforations, but the gripper is brought into action to limit the movement to a distance equal to the exact height of a 40 check form and equal to the distance between two 45 similarly located control perforations sensed as the check strip passes through the gripping unit.

The check feeding devices are shown in Figs. 4, 5 and 6. These devices are adapted to move the check strip 50, after each total printing operation, 40 through a plurality of line spaces amounting to a space of about three and one-half inches of the strip, or a length slightly greater than the narrow side of a check. Of course it is obvious that the proportions of the feed devices or gearing may 45 be varied, or different size clutch disks may be inserted to suit other check sizes.

The feeding devices are connected to the right side of the platen as viewed from the front of the machine (at the left in Fig. 5) this side being 50 supported by a side frame 100 fastened to a carriage brace rod 101. The driving connections are mounted between a tabulator side frame 102 and a bearing bracket 103 fastened to the tabulator base. A tabulator brace bar 104 carries a 55 bracket 105 for supporting a holder 106 for the feed release magnet FM.

The driving means for the feed devices is a cam 107 which is fixed to the tabulator printer shaft 108 borne by frame 102 and bracket 103. 60 This printer shaft turns one complete revolution in a clockwise direction (Fig. 4) during each printing cycle of the tabulator. Cooperating with the cam 107 is a roller 109 mounted on the end of an operating lever 110 fastened to a shaft 65 111 loosely pivoted between the top of bracket 103 and a hole in side frame 102. Shaft 111 also carries an arm 112 which is pivotally connected by a screw 113 to an operating link 114. A spring 115 connected to a tab 116 on link 114, tends to 70 rock the shaft 111 in a counterclockwise direction to maintain constant cooperation between roller 109 and cam 107. However, such cooperation is normally prevented by an armature latch lever 117, the lower end of which abuts against 75

the top of a shoulder 118 on the end of lever 110 opposite roller 109. Lever 117 is loosely pivoted on a rod 119 supported in a pair of ears 120 depending from holder 106. A spring 121 urges the latch lever 117 in a clockwise direction to hold the parts latched until magnet FM is energized. Then the magnet attracts the horizontal arm of lever 117 and rocks the lever in a counterclockwise direction to move the lower end of the lever out of the path of shoulder 118 and permitting the check feeding drive linkage to move as controlled by the periphery of cam 107. Magnet FM is not energized on every cycle of the tabulator, nor on every printing cycle of the machine, but only on total printing cycles when an amount is printed on a check.

The control of cam 107 over the operating linkage is such as to allow the link 114 to lift quickly under the urging of spring 115, and then to draw the link down again positively due to the cooperation of the rising cam surface against roller 109. This all happens on the reset portion of the tabulator total print and reset cycles, so that total printing is finished before the described connections act to move the check strip.

Link 114 is slotted at 122 and 123 and connected to an upper operating link 124 by a pair of screws 125 fastened in link 124. Another screw 126 in link 124 carries a nut 127 with an eccentric shoulder 128 that protrudes into a transverse slot in link 114. Nut 127 may be turned to move link 124 up or down with respect to link 114, thus providing an adjustable length of link between the check feed driving and operating means to allow the operator to determine the starting and ending position of the feed pawl.

Attached to the platen side frame 100 (Fig. 6) is a bracket 129 carrying a hub 130 which forms a bearing for the hub 131 of a rocking drive plate 132. This plate is loosely pivoted on a sleeve 133 extending out of the side of a platen drive gear 134 pivoted on a shouldered stud 135 secured to side frame 100 by nut 136. Also loosely pivoted on sleeve 133 is a ratchet wheel 137 with a sleeve 138 that passes through hub 131. Wheel 137 is normally connected to gear 134 by a pair of pins 139 which protrude from the gear into one of three pairs of holes 140 in the side of the wheel.

The ratchet wheel 137 is driven in a counterclockwise direction (Fig. 4) by a pawl 141 pivoted on a screw 142 in drive plate 132 and held thereon by a U-shaped clip 142. A spring 143 tends to hold pawl 141 in engagement with the wheel. The top of upper link 124 is formed with a hub 143 (Fig. 5) which pivots on the shoulder of a screw stud 144 fastened to plate 132. The link is removably held on the stud so that the connection may be easily broken when the carriage is to be moved or taken out of the machine. For this reason link 124 is held on stud 144 by a thin locking strip 145 which is slotted at 146 to engage in notch under the head of the stud. The strip 145 is pivoted on a screw 147 in link 124 and provided with a finger piece 148 for moving it around the screw. A small projection 149 on the strip fits into a depression in the side of link 124 to hold the strip in locking position.

Through the connection at stud 144, the raising and lowering of link 124 serves to rock plate 132 first in a clockwise and then in a counterclockwise direction. As this is done, pawl 141 first slides idly along the periphery of clutch wheel 137 on the up-stroke, and then on the down-stroke it engages in one of four notches 150 cut in the edge of the wheel to turn it in a counter-

clockwise direction. As the wheel reaches one of the four home positions, it is held there by a retaining detent 151 pivoted on a stud 152 on bracket 129. A spring 153 on the detent, tends to hold it with a tooth 154 thereon projecting into one of the notches 150. The detent maintains such a wheel latching position during the up-stroke of plate 132, and is only thrown out near the end of the up-stroke when the end of a screw stud 155 on plate 132 strikes a cam face 156 on the detent and rocks it to lift tooth 154 away from the clutch wheel. At this time, the pawl 141 engages one of the notches 150 and starts moving the clutch wheel 137 so that even though the detent is released early in the down-stroke of the drive plate, it does not immediately engage a notch 150 but rides idly on the periphery of the wheel until the end of the feed cycle when it again drops tooth 154 into the next notch 150.

Of course when connections are made for feeding, gear 134 always moves with the clutch wheel 137, and it is through this gear that the platen 52 is driven in a manner about to be described.

Driving gear 134 meshes with a pinion 157 secured to the end of the platen shaft 158 by a screw 159. The one end of the shaft is supported by a bearing 160 on frame 100. Also secured to shaft 158 is a driving disk 161 with an opening into which protrudes a keying pin 162. This pin is fastened in a bushing 163 loosely mounted on shaft 158 but fastened to the platen 52 and its stiffening tube 164. As gear 134 is driven by the linkage from cam 107 (Fig. 4) pinion 157 is turned and through disk 161 (Fig. 6) pin 162 and bushing 163, platen 52 is turned therewith.

If it is desired to disconnect the platen from the check feed devices, the platen may be grasped and shifted to the right (Fig. 6) to move the pin 162 out of the opening in disk 161. The platen is located and held in the clutching and declutching positions on shaft 158 by a spring pressed ball 165 in bushing 163. This ball cooperates with either of two grooves 166 in shaft 158. The shaft is held stationary as the platen is shifted, and a shoulder 167 thereon prevents the disk 161 from following the platen to the right.

As the platen is shifted out of engagement with the check feeding devices, it is automatically coupled with the ratchet gear 168 of the ordinary line spacing mechanism. A pin 169 is fastened in a bushing 170 fastened at the right end of the platen. This pin fits into an opening 171 in the side of a clutch collar 172 fastened to the end of shaft 158. An adapter 173 connects the collar 172 to the ratchet 168. When pin 162 is moved out of disk 161 a distance equal to the space between the grooves 166, pin 169 keys the platen 52 with the collar 172 and line space ratchet gear 168.

A manipulative knob 174 (Fig. 6) is provided to turn the platen 52 independently of the check feeding mechanism when the check strip is inserted in the machine. This knob is fastened to the sleeve 133 of driving gear 134 so that the gear may be pushed in to disengage the drive pins 139 from the wheel 137 before the knob is turned manually to wrap the first part of a check strip around the platen. A coil spring 200 presses between frame 100 and the side of gear 134 and tends to hold the gear coupled with the ratchet wheel. The teeth on pinion 157 are wide enough to maintain meshing relationship with the teeth on gear 134 even though the gear is shifted.

When the gear 134 is shifted for disconnection,

ratchet wheel 137 is prevented from following along therewith by a collar 176 fastened to the tubular end 138 of the wheel. This collar is spaced near hub 130 and presses against the side 5 thereof if the wheel tends to move in with gear 134.

After the check strip is inserted so that the first check is near the printing position, the operator turns gear 134 further until pins 139 coincide with the nearest set of holes 140 in ratchet wheel 137. Then he releases the inward pressure on knob 174 and allows the gear to move outward so that pins 139 again engage to couple the gear to the check feed ratchet wheel.

15 If further adjustment is necessary to bring the printing line of the first check into position, the ordinary pressure feed rollers 171 (Fig. 2) may be released while the strip is adjusted.

An opening 178 (Fig. 4) is provided in the top 20 of frame 103 so that the entire platen assembly on shaft 158 may be removed. The end of the platen shaft is normally held down in opening 178 by a retaining arm 179 pivoted on frame 100 and swung down against the top of bearing 160 25 where it is held by a screw 181.

A roll carrying bracket 182 is secured to frame 100. This bracket may be used to support one end of a paper roll should the checks or other record paper be assembled on a roll rather than a fan-folded strip.

The carriage is held in the check feed position by a plunger 183 (Fig. 4) which protrudes into a hole in a carriage bar 184 movable with the platen frame. The plunger slides in a tube 35 185 fastened to a fixed carriage bar 186. A compression spring 187 tends to push the plunger into the carriage locking position, but the knurled end may be grasped and the plunger pulled out of bar 184 while the carriage is shifted. Then the plunger 40 may be released to again lock the carriage in a new position.

In Fig. 9 there is shown a diagram of the new wiring connections in a tabulator such as that of the Mills' patent referred to hereinbefore, to 45 properly energize the feeding and gripping magnets FM and GM. A check feed switch CFS may be closed to select feed control by making partial connection between the energized tabulator lines 201 and 202. Then when a total such as 50 16.58 (Fig. 7) is to be printed, the total switch magnet TM is energized to close contacts 175 in series with magnet FM. As the total print and reset cycle is in operation, and after the total impression is made, cam contacts P18 are closed by 55 a cam on the print shaft and the feed magnet FM is energized over the circuit from line 201, switch CFS, contacts 175, magnet FM, contacts P18 and line 202. The magnet then rocks lever 117 to release the check feed operating linkage. Of course, 60 feeding is not started immediately upon energization of the magnet, because the depression in the cam first allows retraction of the linkage 114, 124 and pawl 141 before the actual feeding movement is started.

65 Near the end of the feeding operation the gripping magnet GM goes into action under control of a marginal perforation to stop the check strip in an exact position for the next name and total print line. Although the brush 76 passes 70 through all of the marginal perforations 51 on the right side of the strip, only one perforation per check is effective to control gripping, and that is the one encountered near the end of the feeding cycle as determined by the late closing of cam 75 contacts P17. Therefore, late in the total print-

ing and check feeding cycle, if the cover 72 (Figs. 2 and 3) is closed, contacts 97, 97a and 84 will be closed, and contacts P17 (Fig. 9) are closed, so that as soon as the next marginal perforation 51 appears between brush 76 and contact insert plate 78, magnet GM is energized. The circuit includes line 201, switch CFS, plug socket 189, contacts 97, gripper magnet GM, contacts 84, brush 76, through perforation 51, plate 78, contacts 97a, plug socket 190, contacts P17 and line 10 202. The energized magnet GM then actuates lever 91 to press the friction block 96 against the strip to hold it in position momentarily until the feed motion of the platen ceases after which contacts P17 again open to prevent gripping until 15 the next total print cycle. Plug sockets 189, 190 provide means for shunting the gripper connections or for plugging them to controls other than contacts P17 and switch CFS.

When the feeding movement of the pawl 141 is 20 gauged to give an exact feeding movement, it is then the function of the gripper merely to hold the strip in position rather than both stop and hold the strip.

While there is disclosed herein the novel features of the invention as applied to one form, it will be understood that various omissions, substitutions and changes in the form and details of the devices illustrated and in their operation may be made by those skilled in the art without departing from the spirit of the invention. It is the intention, therefore, to be limited only as indicated by the scope of the following claims.

What is claimed is as follows:

1. In a machine for printing and feeding a 35 record strip, a platen for holding and feeding said strip, a line spacing means for operating said platen, a form feeding means for operating said platen to feed the strip a plurality of line spaces, connections between said platen and the spacing 40 means, connections between said platen and the feeding means, and means for shifting said platen to make either of the connections effective and the other connections ineffective.

2. In a machine for feeding a record strip 45 divided into separate forms, a platen for holding said forms, means for operating said platen, clutch devices including a ratchet wheel between said platen and operating means, a pawl for operating said wheel, a linkage between said pawl and the platen operating means, an eccentric in said linkage, and means for adjusting said eccentric to determine the extent of movement of said wheel by the pawl.

3. In a machine for feeding a record strip 55 divided into forms, a strip feeding cam, a lever cooperating with said cam, an armature latch for holding said lever out of the path of said cam, a magnet for operating said latch to release the lever, means for energizing the magnet, and 60 means operated by the lever for moving the strip from form to form.

4. In a machine for feeding a record strip divided into forms, means for holding and moving the strip, a line spacing means, a clutch between 65 said holding means and said spacing means, a feeding means for moving the strip from form to form, a second clutch between said holding means and said feeding means, means for selectively making either clutch effective, a 70 manipulative means for operating said strip moving means, a third clutch between said holding means and said feeding means, and means associated with said manipulative means for operating said third clutch to make it ineffective when 75

the strip is fed manually by the manipulative means.

5. In a machine for feeding a strip divided into forms, a platen for holding said strip, a notched ratchet wheel connected to said platen, a pawl for operating said wheel, means for retracting and operating said pawl to turn said wheel, a square toothed detent cooperating with the notches in said wheel to hold it in position, and means on 10 said pawl operating means for operating said detent to lift the tooth away from the wheel when the pawl is fully retracted.

6. In a machine for feeding a strip divided into forms with a plurality of perforations spaced in 15 each form, means for sensing the perforations, means for feeding the strip past the sensing means, means for selecting one of said plurality of perforations to control the stopping position of the strip, and means under control of the sensing 20 means when cooperating with the selected perforation for stopping the strip.

7. In a machine for controlling the feeding of a continuous strip divided into check forms with a plurality of marginal perforations in each check, 25 means capable of feeding said strip a slightly greater distance than the space from check to check, means for sensing the perforations in the strip, and a gripping means controlled by said sensing means for stopping the strip and confining 30 the movement of the strip to the exact distance between checks.

8. In a machine for controlling the feeding of a continuous strip divided into check forms with a plurality of marginal perforations in each check, 35 means capable of feeding said strip a slightly greater distance than the space from check to check, means for sensing the perforations in the strip, means for selecting one of said plurality of perforations for effective cooperation 40 with said sensing means near the end of the feeding operation, a strip gripping means, and means under control of said sensing means for operating said gripping means to stop the strip after a feed of one check space when the selected one of the 45 perforations is sensed.

9. In a machine for printing names and totals on a continuous strip divided into check forms with marginal perforations, means for feeding

said strip from form to form approximately, means for printing on a line of the check form, means for gripping the strip, a magnet for operating the gripping means, means for sensing the marginal perforations in the check strip, and means under control of said sensing means for energizing said magnet to operate the gripping means to stop the strip in an exact check printing position.

10. In a machine for feeding a strip, a feed control box the sides of which guide the strip, a hinged cover on said box under which said strip may be inserted when it is opened, and means for controlling the feeding of the strip including electrical contacts which are operated by said cover 15 to make the feeding devices effective when the cover is closed and ineffective when the cover is opened.

11. In a machine for feeding a strip with marginal perforations, means for feeding the strip, a box through which the strip is fed, a fixed sensing brush in said box for sensing said perforations, a hinged cover on said box which may be lifted when a strip is to be inserted, a metallic insert on said cover aligned with said brush so that contact 25 may be made when a perforation passes between them, a source of electrical current, a contact in series with said insert which is closed when said cover is closed, a circuit closed by said brush through a perforation, and means under control 30 of said circuit for controlling said strip feeding means.

12. In a machine for printing names and totals on a continuous strip divided into checks with marginal perforations, a strip feeding mechanism 35 for feeding said strip from check to check, a latch for preventing effective operation of said mechanism, a magnet for tripping said latch, means for energizing said magnet as an incident to total printing, means for gripping said strip to hold it 40 in exact printing position near the end of the operation of said mechanism, a magnet for operating said gripping means, means for sensing the marginal perforations, and connections including said sensing means for energizing said gripping magnet.
